CHAIR

Stapleton Long, Morristown, Tenn., assignor to The Berkline Corporation, West Springfield, Mass.

Filed Aug. 30, 1972, Ser. No. 284,940

Term of patent 3½ years

Int. Cl. D6—01

U.S. Cl. D6—39

FIG. 1 is a view, in front elevation, of a chair showing my design; and

FIG. 2 is a view, in side perspective, of the chair of FIG. 1.

The chair back is plain and conventional throughout and the side not shown is identical to that shown.

I claim:

The ornamental design for a chair, as shown and described.
